UNITED STATES PATENT OFFICE.

ROBERT McC. JOHNSTONE, OF ROSELLE PARK, NEW JERSEY, ASSIGNOR TO CAMERON MACHINE COMPANY, OF BROOKLYN, NEW YORK, A CORPORATION OF NEW YORK.

SLITTING MEANS.

Application filed May 2, 1923. Serial No. 636,134.

REISSUED

This invention relates to slitting means steel connected by blocks 9, the cutter being and is more particularly designed as an improvement upon the construction disclosed in the application of Cameron and Birch for 5 slitting means, filed August 25, 1920, Ser. No. 405,997.

One of the difficulties encountered in score cutting mechanism is the chattering of the cutters due to the vibration of the machine, 10 and this condition is especially found in heavy duty machines. This chattering is due to the fact that heretofore the cutter supporting lever was relatively cumbersome 15 being made of cast iron and therefore when this lever received an outward impulse, due to vibration, it would tend either to continue to leave the backing roll or not respond quickly enough to its spring pressure to follow the backing roll on the rebound thus 20 causing a hammering or pounding.

The main object and feature of this invention is to provide means whereby this difficulty may be overcome and the invention consists of the features of construction, a 25 preferred embodiment of which is disclosed in the specification and accompanying drawings.

In said drawings:

Fig. 1 is a fragmentary view in rear elevation of a slitting device embodying the invention.

Fig. 2 is a fragmentary vertical sectional view of parts of a slitting and winding machine showing the slitting device of my invention in side elevation.

Fig. 3 is a fragmentary view in front elevation of a slitting device embodying the invention.

Fig. 4 is a view substantially similar to Fig. 2 but on an enlarged scale.

Fig. 5 is a view substantially similar to Fig. 3 but on an enlarged scale and with parts broken away and in section.

1 indicates a score cutter that acts against 45 a backing roll which may be either one of the winding drums but, preferably and as herein disclosed, it is a separate roll 2 just below the front winding drum 3.

Preferably, a rocking support 4 and a carrier 5 transversely adjustable on the rocking support are used as supporting elements of the score cutter device, cutter supporting lever 6 being mounted at its lower end on a pivotal support 7 formed by the carrier. 55 Lever 6 consists of two thin cheek plates 8 of

rotatably mounted between the cheek plates, and one block being arranged above and the other below the cutter. Pivotal support 7 of carrier 5 consists of two bearings as shown 60 and the lower block is provided with two pins 10 that rest in the bearings. Carrier 5 may be of any suitable material such as cast iron. Cutter supporting lever 6 is arranged in an upright position and secured to its 65 lower end, preferably on the lower block and at a point below its pivotal support, is a spring means 11 that bears against tail 12 of the carrier to thereby press the cutter against the backing roll. Mounted on lever 6 is a 70 pan 13, preferably of aluminum, containing water, oil or other substance, and 14 is a wick extending from said pan up between the lower block and the cutter. In some cases it is desirable to use a separating device that engages between slotted sections 15 before winding. In this case, a separating bracket 16, preferably of aluminum, is pivotally mounted at 17 at the upper end of lever 6. A handle 18 also of aluminum is 75 employed to turn this bracket into a forward or a rearward position, and a spring 19 anchored at 20 on the lever holds the bracket in either its retracted or advanced position as it will be seen that the spring passes over 80 center 17 when the bracket is adjusted. Carried by the bracket is a separator holder 21 secured in position by bolt 22 passing through slots 23 which latter is elongated transversely so that the holder can be brought 85 into alignment with the slit between adjacent sections. The bracket carries separator blade 24 held in position by screw 25.

The cutter is brought into and out of engagement with the backing roll by turning 95 rocking support 4 and the separator is thrown in and out of action by means of handle 18.

By reason of the light construction of the cutter supporting lever, the objectionable 100 chattering and hammering is to a large extent obviated.

I claim:

1. Slitting means comprising: a backing roll, a score cutter, means for mounting the 105 score cutter including two cheek plates, two blocks, one above and one below the cutter, connecting the cheek plates, a pivotal support engaging the lower block, and a spring member, for pressing the cutter against the 110

backing roll, connected to the lower block.

2. Slitting means comprising: a backing roll, a score cutter, a pivotal support, an upright cutter supporting lever mounted at its

5 lower end on the pivotal support, and a spring member, for pressing the cutter against the backing roll, connected to the lower end of the cutter supporting lever.

3. Slitting means comprising: a backing 10 roll, a score cutter, a pivotal support, an upright cutter supporting lever mounted at its lower end on the pivotal support, and a spring member, for pressing the cutter against the backing roll, connected to the 15 lower end of the cutter supporting lever below its pivot point.

4. Slitting means comprising: a backing roll, a score cutter, an upright cutter supporting lever consisting of two cheek plates, 20 one above and one below the cutter, connecting the cheek plates, a pivotal support engaging the lower block, and a spring member, for pressing the cutter against the backing roll, connected to the lower block.

25 5. Slitting means comprising: a backing roll, a score cutter, an upright cutter supporting lever consisting of two cheek plates, one above and one below the cutter, connecting the cheek plates, a pivotal support en-

gaging the lower block, and a spring member, for pressing the cutter against the backing roll, connected to the lower block below its point of pivotal support.

30 6. Slitting means comprising: a backing roll, a score cutter, a pivotal support, an upright cutter supporting lever mounted at its lower end on the pivotal support, a spring member, for pressing the cutter against the backing roll, connected to the lower end of the cutter supporting lever, a pan, containing liquid, mounted at the lower end of the lever, and a wick from said pan extending above the lower block and below the cutter into engagement with the latter.

35 7. Slitting means comprising: a backing roll, a score cutter, a pivotal support, an upright cutter supporting lever mounted at its lower end on the pivotal support, a spring member, for pressing the cutter against the backing roll, connected to the lower end of the cutter supporting lever, and a web separating device pivotally mounted at the upper end of the lever.

40 50 Signed at Brooklyn in the county of Kings and State of New York this 23 day of April, 1923.

55 ROBERT McC. JOHNSTONE.
